UNITED STATES PATENT OFFICE.

RALPH E. MARBURY, OF PITTSBURGH, PENNSYLVANIA, ASSIGNOR TO WESTINGHOUSE ELECTRIC & MANUFACTURING COMPANY, A CORPORATION OF PENNSYLVANIA.

RESISTOR FOR SHUNTED CONDENSERS.

Application filed October 1, 1923. Serial No. 665,834.

My invention relates to resistors and more particularly to resistors for use in connection with high-voltage, direct-current condensers, lightning arresters, or the like apparatus 5 to which said resistors are adaptable. Still more particularly, it relates to liquid resistors capable of maintaining a balance between the units of a condenser system or other apparatus.

Under some conditions, it has been found desirable to parallel the condenser with resistance relatively low compared to the resistance of the condenser, in order to control the voltage distribution or balance as desired.

Some types of resistors, particularly those consisting of a tubular element having resistor wire wound thereon, have been found undesirable because of their high initial cost 20 and further because of their excessive use of energy and consequent high cost of operation.

It has also been found that, in the use of resistors of other than liquid material, an unbalanced condition often arises in condensers and other apparatus with which they are associated, which has resulted in a puncture of the dielectric and a breaking down 25 of the unit and, in some instances, the whole system. This result is due in part to the fact that the elements of the resistor contain impurities, vary in thickness and density at different points and do not respond to produce a substantial balance between electrodes 30 spaced an equal distance apart. It has been particularly found in carbon resistor elements that changes in their operation result after a period of time and by reason of variations in temperature, and that they do not 35 have a uniform action.

To overcome this, I have devised a resistor in which the electrodes are immersed in a liquid and which will automatically maintain an even balance between the spaced electrode 40 elements.

One of the objects of my invention is to overcome these defects and to provide a liquid resistor which will automatically maintain electrodes immersed therein in equally spaced relation to each other and comprising a plurality of steps, in a state of substantially perfect balance, so that in condenser systems, lightning arresters and other apparatus with which they may be operable,

a concentration of voltage on a single unit 55 will not occur and the breaking down of the system for this or other similar reasons will be obviated.

My invention consists substantially in providing a sealed receptacle containing an organic or inorganic liquid, such as, for instance, a mixture of xylene and alcohol, in which the electrodes forming a plurality of steps and connected to the terminals of the condenser systems, lightning arresters, or 60 other apparatus, are immersed so that a condition of balance will be maintained between the respective steps and throughout the system. It is observed that, although in a system of condensers, the working conditions 65 thereof may vary from time to time, yet they will be maintained in balance in respect to each other by the automatic operation of the liquid resistor common to all electrodes of a plurality of steps contained in a single container which combination I have devised and which thereby overcomes the defects experienced in the operation of resistors heretofore employed.

Referring to the accompanying drawings 70 in which like reference characters indicate like parts,

Fig. 1 is a cross-sectional view of my resistor showing a series of four electrodes 75 therein, and

Fig. 2 is a diagrammatic view of a condenser system coupled with my liquid resistor.

Referring more particularly to the drawing, I provide a hermetically sealed, preferably glass, tube 1 into which I seal a plurality of similar conductors or electrodes 2, 3, 4, and 5, in this instance the number being four, but which, it is well understood, may be varied as the conditions require. The electrodes are spaced substantially equal distances apart. Within the tubular container 1 and substantially filling the same, I provide liquid, indicated at 6, of high resistance and which, in the particular apparatus herein described, is a mixture of xylene and alcohol.

The application of my resistor will be obvious from reference to Fig. 2. The respective condenser units or systems 7, 8 and 9 have their terminals 10, 11, 12 and 13 connected to the electrodes 2, 3, 4 and 5 of the resistor 1 by the conductors 14, 15, 16 and 17,

respectively, and by these means the condenser systems and the resistor are assembled in the desired operative relation.

Although I have referred to the maintenance of balance by my resistor between electrodes equally spaced apart, yet it is obvious that the balance between them will be retained under certain conditions although the electrodes may be spaced apart unequally. When the capacity of the respective units or systems of condensers connected to the electrodes is equal the electrodes should be equally spaced apart in order to effect this balanced relation; but if the capacity of these units or systems is greater or less in reference to each other then their respective electrodes should be correspondingly spaced a greater or less distance from each other.

Because of impurities therein and for other reasons, insulation of the solid type varies widely in insulation resistance in condenser units. The voltage per unit thickness may be equally distributed at first but may divide unevenly as a result of the unequal insulation resistances developed at various points in the material. At one point in a single insulation or dielectric, the voltage may be low, while at another point it may be very high, owing to the lower specific resistance of the insulation or dielectric.

As, hereinbefore stated, balancing resistors of the solid type have failed to maintain balance between a plurality of steps co-operating with a plurality of condenser units and, by providing a liquid resistor element of uniform density not affected by temperature and time, acting upon the electrodes of a plurality of steps in a common container I am enabled to utilize such a liquid to maintain a balanced relation between the electrodes comprising the respective steps which are immersed therein and with which the condensers are ultimately connected. This result is accomplished not only because of the uniformity in purity and density at all points of the resistor element, but because the homogeneous liquid covers all electrodes at all times.

An examination of the operation of my liquid resistor will be found to show that, although from time to time, the resistance of the liquid resistor may change, the relation of balance of each individual electrode and of each step to the others is constantly and automatically maintained.

As a preferred mode of application of my invention, the conductors 14 and 17 may be

a high-voltage direct-current line, the condensers 7, 8 and 9 being utilized as lightning arresters for discharging voltage surges of steep wave front on the line.

It will be seen from the foregoing that I have provided a resistor which will overcome the defects found in the prior art and which is efficient, positive and automatic in operation, simple in construction and of comparatively cheap cost. It will be understood that, although I specifically mention the use of the mixture of xylene and alcohol, I do not wish to be limited thereby and am aware that many other liquids and liquid mixtures are adaptable for this use, such as acetone, toluene, benzol and other liquids having similar properties.

I claim as my invention:

1. The combination with a plurality of condensers connected in series, of a shunting resistor comprising a single container having therein a liquid in which are immersed terminal and intermediate electrodes connected to terminal and intermediate points of said condensers.

2. The combination with a plurality of condensers connected in series, of a shunting resistor comprising a single container having therein a mixture of xylene and alcohol, in which are immersed terminal and intermediate electrodes connected to terminal and intermediate points of said condensers.

3. The combination with a plurality of condensers, of a shunting resistor comprising a sealed tubular container having therein a mixture of xylene and alcohol, in which are immersed three or more electrodes electrically connected to a corresponding number of condenser terminals.

4. The combination with a plurality of condensers of a resistor comprising a container having therein a liquid, in which are immersed a plurality of sets of electrodes to provide a plurality of sets of resistors which are connected to said condensers.

5. The combination with a plurality of condensers of a resistor comprising a container having therein a mixture of xylene and alcohol in which are immersed a plurality of sets of electrodes to provide a plurality of sets of resistors which are connected to said condensers.

In testimony whereof, I have hereunto subscribed my name this 26th day of September, 1923.

RALPH E. MARBURY.
